UNITED STATES PATENT OFFICE.

EDWARD MORTON NEWCOMB, OF MINNEAPOLIS, MINNESOTA.

LOCK-HINGE.

SPECIFICATION forming part of Letters Patent No. 355,408, dated January 4, 1887.

Application filed June 1, 1886. Serial No. 203,775. (No model.)

To all whom it may concern:

Be it known that I, EDWARD MORTON NEWCOMB, of Minneapolis, in the county of Hennepin and State of Minnesota, have invented certain Improvements in Lock-Hinges, of which the following is a specification.

The aim of my invention is to provide an automatic hinge for locking external blinds in an open position, which may be cheaply constructed, which shall hold the blind with great security and be free from liability of breakage, and which will afford no obstruction to the application and removal of the "storm-sash," commonly applied during the winter 15 season to the window-casing outside of the ordinary sash.

My hinge is designed more particularly for use at the lower end of the blind, the upper end of which may be sustained by a hinge of 20 any ordinary or approved construction.

In the accompanying drawings, Figure 1 is a perspective view of the two parts of my hinge separated from each other. Figs. 2 and 3 are respectively a face view and a lower end 25 view of the hinge in its closed position. Figs. 4 and 5 are respectively an outside face view and a lower end view of a hinge in its open position.

Referring to the drawings, my hinge consists of two parts, A and B, each cast complete in one piece, of the form represented in Fig. 1. The leaf A, which is designed for attachment to the wall or window-casing, consists of a flat plate adapted for attachment to 35 the outer face of its support, and provided with a projecting horizontal rib, *a*, having therethrough a vertical eye or opening, *b*, and at the rear edge horizontally-projecting lips *c c'*, which are arranged in such relation with 40 each other as to leave a vertical opening between them to seat the opposite leaf, as presently described. It will be perceived that the opening *b* is of a narrow flat form at the forward side of the leaf, but enlarged to a circular form at the rear.

The leaf B consists of a flat plate provided with an outwardly and downwardly projecting pintle, *d*, flattened on its side face, with a depending lip, *e*. The pintle *d* is passed downwardly through the eye *b*, and when the hinge

is closed the pintle is held by the weight of the blind at the rear or large end of the eye, as shown in Figs. 2 and 3. As the blind is opened the pintle revolves in the large end of the slot until the opening movement is completed. During this movement the lip *e* is carried to a position opposite the space between the lugs *c c'*, whereupon the weight of the blind will cause the outer leaf to swing inward, so that the flattened pintle will enter the flattened portion of the eye and the lip *e* engage between the studs *c c'*, as shown in Figs. 4 and 5. By this interlocking action the swinging leaf and the blind are secured rigidly in position, so that the closing of the blind is impossible. 55 60 65

It is to be noted as a peculiarity of my hinge that its parts interlock at two points widely separated from each other, whereby it is held with a security not attainable in those blinds which rely simply on a locking action of the pintle or a shoulder on the end of the pintle. 70

In order to unlock the hinge, it is only necessary to push the lower end of the blind outward in the direction indicated by the arrow 75 in Figs. 4 and 5, the effect of which is to disengage the lip *e* and carry the pintle into the widened end of the eye, so that it may turn therein.

The essence of my invention resides in the 80 employment of a flattened pintle in combination with an eye having one side enlarged to permit the application of the pintle, and the other side restricted in width to embrace and hold the same, and in the provision of surfaces at a distance from the pintle adapted to 85 interlock by a horizontal movement of the blind; and it is manifest that the form and configuration of these parts may be variously modified without affecting their mode of action 90 or passing beyond the scope of my invention.

Having thus described my invention, what I claim is—

1. In a blind-hinge, the leaf provided with the eye enlarged at one side, in combination 95 with the leaf having the flattened pintle adapted to revolve in the enlarged side of the eye, but lock firmly in the opposite side of the same, substantially as described.

2. In a blind-hinge, the leaf provided with 100

the eye elongated horizontally, and shoulders *c c'* at the outer edge, in combination with the leaf provided with the pintle and with the lip *e*, substantially as described.

5 3. In a blind-hinge, the leaf A, having the eye elongated horizontally and reduced in width at one end, and a locking-shoulder at a distance from said eye, in combination with the leaf B, having the flattened pintle *d*, and
10 the lip *e*, substantially as described.

In testimony whereof I hereunto set my hand this 27th day of March, 1886, in the presence of two attesting witnesses.

EDWARD MORTON NEWCOMB.

Witnesses:

W. C. KRISE,
JACOB BUYER.
